Specification of Letters Patent. Patented July 24, 1917.

Application filed April 24, 1916. Serial No. 93,285.

To all whom it may concern:

Be it known that I, ALFREDO BENITO VASQUEZ, a citizen of the United States of America, residing at No. 142 Amistad street, Havana, Cuba, have invented new and useful Improvements in Machines for Numbering and Marking Bags, of which the following is a specification.

This invention relates to printing machines and in particular to a machine for numbering bags or sacks and printing thereon identifying matter, such as the brand of goods to be contained therein and the name and address of the producer, the primary object being to improve upon my prior invention which is covered by Cuban Patent No. 2137, dated September 7th, 1914.

The invention disclosed in the said patent comprises a frame having bag feeding means, a rotatable printing drum having printing wheels adapted to consecutively number the bags as they pass through the machine, and means for inking the type faces of the printing wheels.

The improved machine possesses numerous advantages over the previously patented one. In the first place, it is capable of marking and numbering bags of different dimensions, it only being necessary to change some of its component parts for this purpose. By the term "marking" is meant the printing of words upon the bags, as distinguished from numbers. Furthermore, it can mark alone, or number, or can do both operations at the same time. The machine can also be made to repeat the same number an indefinite number of times, when this is desired. In addition to these advantages, it is capable of stacking the bags which have passed through the same at the foot of the machine, or at any distance from the same, or to make a series of stacks or piles positioned equi-distant or at varying distances, according to the desire of the operator.

With these and other advantages in view, the invention consists specifically in the construction and combination of parts described in the following specification and illustrated in the accompanying drawings, wherein similar reference characters indicate like parts, and in which:

Figure 1 is an elevation of the left hand side of the machine, considering the position of the operator when facing the feed end of the machine, the machine being shown partly broken away;

Fig. 2 is a similar view of the right hand side of the machine;

Fig. 3 is a rear elevation of the machine;

Fig. 4 is a front elevation thereof;

Fig. 5 is a left hand side view of the power transmission mechanism for the rollers of the bag conveyer;

Fig. 6 is a plan view of the transmission mechanism for the stacking device, the same being partially broken away;

Fig. 7 is a longitudinal sectional view through the printing drum, showing all of the typewheels with the exception of the units wheel in their normal, zero position, the units wheel being in position for printing the "9," with the toothed operating device in its advanced position;

Fig. 8 is a transverse sectional view on line 8—8 of Fig. 7; and,

Fig. 9 is a similar view on the line 9—9 of Fig. 7 looking in the opposite direction, but showing the hundreds wheel and the operating device in full lines in the position they will assume just preceding the movement of the three wheels of lowest order into position for printing the numeral 100, the operating device being shown in dotted lines in the succeeding advanced position.

In the drawings the numeral 1 designates the frame of the machine, which may be constructed in any suitable form. A transversely extending cylindrical drum 2 is rotatably mounted above the body of the frame upon horizontal trunnions 3, which are journaled in vertical standards 4 rising from the body of the frame. The drum is provided in its outer, circumferential wall with longitudinal slots 5 and 6, which are substantially diametrically opposite to each other and are intended for purposes which will be set forth fully hereinafter.

Both of the trunnions 3 project laterally from the corresponding standards of the frame and a large gear or spur wheel 7 is secured fixedly to the trunnion which protrudes from the right hand side of the machine (see Fig. 4 in particular). This gear meshes with a pinion 8 which is loosely mounted upon a horizontal stub-shaft 9 projecting laterally from the right hand side of the frame 1 in parallel relation with the axis of the drum 2. The pinion 8 in turn meshes with a smaller pinion 10 which is fixedly secured to the drive shaft 11 extending transversely through the frame and journaled in suitable bearings. At the left hand

side of the frame, a belt pulley 12 is connected with the drive shaft. This pulley is a clutch pulley and is adapted to be shifted into and out of operative connection with the drive shaft, primarily, by means of the hand lever 13. A spring 14 tends normally to maintain the lever 13 in such a position that the pulley clutch will be inoperative, or disconnected from the drive shaft. The lever 13 is provided adjacent to its pivot 15 with a lateral projection 16, which is adapted to be engaged by one of the angularly arranged fingers 17 of a pivoted locking member 18 mounted upon the frame of the machine, when the hand lever 13 is in its other position, wherein the pulley clutch is operative. A spring 19 maintains the locking member 18 normally in its operative position just mentioned. This locking member is provided with a handle 20 by means of which it may be manually operated by a person standing at the left hand side of the machine. From this position the hand lever 13 is also readily accessible for manual operation. In order that the pulley clutch may be rendered inoperative instantly by a person when at either side of the machine, either under ordinary conditions or to prevent some accident, a foot lever 21 is carried by the frame 1 and is connected by means of a flexible member, such as a cord or the like, 22 with the other finger 23 of the locking member. This flexible member passes around suitable guide pulleys 24, so that, when the foot lever is depressed by placing a foot upon the pedal 25, force will be exerted upon the last-mentioned finger of the locking member in a downward direction, thereby moving the engaging finger 17 into its inoperative position, wherein it is cleared by the projection 16 of the primary operating lever 13 for the pulley clutch mechanism. After the lever 13 has been released in this manner, the locking member will automatically assume its operative position, upon inward movement of the said lever into its operative position, closing the clutch. The pulley 12 is intended to be connected by means of a belt (not shown) with any suitable prime mover (also not shown).

The drum 2 contains the printing element proper, which is composed of a plurality of typewheels 26 mounted for independent rotary movement upon the shaft 27, which latter extends axially through the frame, but eccentric with respect to its axis. The opposite ends of the shaft 27 are normally held within radial slots 28 in the ends of the drum by means of the opposed set screws 29 in such a position that the type faces 30 of each wheel will protrude through the slot 6 in the outer drum wall to an extent just sufficient for printing purposes. By adjusting the screws 29 in opposite directions, the shaft 27 may be adjusted ra-

dially to render the typewheels either operative or inoperative, as may be required in practice under certain conditions. Each typewheel has a ratchet portion 31 provided with equi-distant teeth 32 corresponding in number and positions to the respective type faces of the wheel. In rear of one of the teeth of each typewheel ratchet (considering the direction of step-by-step movement of the wheel) a deep recess 33 is provided for a purpose which will be described presently. In the normal position of the printing element, the recesses 33 of all of the type wheels will be disposed in axial alignment and the type faces bearing the characters "0" will be situated in operative, printing position projecting through the drum slot 6. The recess 33 of each typewheel is disposed diametrically opposite to the type face representing the printing character "0." The utility of this arrangement will soon be apparent.

In providing means for operating the respective type-wheels of the printing element to bring type faces producing consecutive numerals into operative position in proper sequence of time during the rotation of the printing drum, radial arms 34 are pivotally connected to the shaft 27 adjacent to the ends of the printing element constituted by the typewheels. These arms project past the peripheries of the typewheels and are provided at their outer ends with bearings 35 for a rock-shaft 36, which is disposed parallel to the shaft 27. Upon this rock-shaft, a plurality of actuating fingers 37 are fixedly connected and correspond in number to the respective typewheels. Each actuating finger is disposed adjacent to the ratchet of the corresponding typewheel so that its engaging extremity may operatively engage the teeth of the ratchet under certain conditions which will be described more fully hereinafter. The actuating fingers are angularly displaced upon the rock-shaft and their relative angular arrangement is such that the engaging extremities thereof establish a spiral imaginary line. The finger for the units wheel, which is at the right hand end of the printing element in Fig. 7, is disposed with its engaging extremity the innermost one of the series. It may be stated at this point that the depths of each wheel recess 33 is such that, when the actuating finger for the typewheel of highest order is in engagement with the ratchet thereof at any point other than within its recess 33, all of the other actuating fingers are accommodated within the recesses 33 of the corresponding typewheels. At least one of the actuating fingers is maintained in engagement with its corresponding typewheel at any time, through the influence of springs 38, which connect the shaft 27 with radial arms 39 projecting from the opposite ends

of the rock-shaft 36. The ends of the rock-shaft are also connected by means of connecting rods 40 with cranks 41 provided upon one section of the crank shaft 42, 5 which shaft is journaled in the printing drum in parallel relation to its axis and exteriorly with respect to the printing element. The throw of each crank 41 is such that, at each revolution of the crank shaft, the rock-shaft with its supporting arms 34 will be oscillated through an angle sufficient to advance one or more of the typewheels one step, and then to become retracted. Power is transmitted to the crank shaft 42 by mechanism which will now be described.

The outermost ends of both sections of the crank shaft just mentioned protrude from the opposite ends of the printing drum and a star-wheel 43 is attached fixedly to the 20 protruding end of that section of the crank shaft which does not bear the crank 41. The points or teeth of this star-wheel are adapted to contact with a plurality of stationary pins 44 which project axially from an annulus 45 which is secured to the standard 4 of the machine frame at the right hand side of the machine. The ratio of the pins 44 to the teeth of the star-wheel is such that the crank shaft 42 in the printing drum will be given 25 a complete rotation during each of its revolutions about the axis of the printing drum in the operation of the machine. A spring-pressed pawl 46 is mounted upon the printing drum and is operatively associated with 30 the star-wheel 43 to retain the same and permit only step-by-step movement thereof. In order that the printing element may be rendered temporarily inoperative at will, the two sections of the crank shaft 42 are connected together by means of a clutch 47. A 35 clutch-throwing lever 48 is fulcrumed at 49 within the drum and is connected with the inner end of a spring-pressed push button device 50 carried by the drum at one end 40 thereof. The push button normally maintains the clutch in operative position so that the sections of the crank shaft are connected for simultaneous rotation. When it is desired to open the clutch, it is merely necessary to push the button 50 inwardly, after 45 it has been given a quarter turn, owing to the provision of a key upon the button which is intended to move through a key-way in the drum. After the push button has 50 reached its innermost position, it is given another quarter turn to cause it to be locked by the said key against return movement. Operation of the clutch in this manner will 55 render the printing element inoperative, so that the machine will not number the bags, but will only mark the same with the type faces which are positioned immovably upon the periphery of the drum. These type faces are designated by the numeral 51. 60 When it is desired to number again, it is

merely necessary to give the push button a reverse quarter turn until the key-way is found, whereupon the retracting spring will automatically restore it to its normal position and will impart the movement to the 70 clutch-shifting mechanism to render the same again operative.

The printing element proper of the printing drum and the operation thereof will now be described further. In the first place, it 75 should be stated that each typewheel is secured temporarily at the end of each step-by-step movement by means of a retaining pawl 52, which is spring-pressed and is adapted to engage the ratchet teeth of the 80 corresponding typewheel successively during the movement of the wheel about its axis. Now, assuming that the printing element proper is in its normal position with the cypher type faces of all the typewheels 85 in operative, printing position, the engaging extremity of the actuating finger for the unit wheel will be in engagement with the tooth of the ratchet of said wheel which is disposed immediately in rear of its recess 33 90 (considering the direction of rotation of the wheel). Incidentally, this particular tooth is diametrically opposite to the tooth immediately in rear of the type face which represents the "0." Assuming also that the printing drum is in its numbering position with its slot 6 disposed lowermost, during the next succeeding semi-rotation of the drum, the unit wheel will be advanced one step by the actuating finger therefor and the 100 type face "1" will be brought into operative, printing position. None of the other printing wheels will be affected, since the actuating fingers therefor will all be maintained by the finger for the unit wheel in spaced 105 relation to their respective ratchets. During the next semi-rotation of the drum, the actuating finger for the unit wheel will be retracted for engagement with the next succeeding tooth of the ratchet of the said wheel. 110 At this point, the type faces of the printing element will be adapted to print the numeral "000001." This is the equivalent of the mere numeral "1." When the said movements of the operating mechanism for the 115 typewheel have been repeated eight times; that is, when the unit type wheel has rotated from "1" to "9," then the actuating finger for the unit wheel falls into the recess 33 in the ratchet of the said wheel, upon assuming its retracted position. This permits the adjacent actuating finger for the tens wheel to engage the tooth of its ratchet which is disposed immediately in rear of the recess 33 therein. Consequently, during 120 the next semi-rotation of the drum, both the units and the tens wheels will be advanced one step, thereby bringing the cipher on the unit wheel and the numeral "1" on the tens wheel to operative position. The print- 125 130

ing element will thus be adapted to print the numeral "000010." When the actuating fingers are retracted during the next semi-rotation of the drum, the actuating finger 5 for the unit wheel will ride out of the recess 33 of said wheel and will engage the ratchet tooth immediately in rear of the said recess, thereby elevating the actuating finger for the tens wheel into inoperative 10 position. During the next eight movements of the operating mechanism for the type-wheels, the unit wheel will be advanced from "1" to "9." Then, the actuating finger for the unit wheel will again fall into 15 the recess of the corresponding ratchet, so that, during the next forward movement of this actuating finger, both it and the one for the tens wheel will be operative and will cause both of these wheels to advance one 20 step, thereby bringing the cipher of the unit wheel and the numeral "2" of the tens wheel into operative position to print the numeral "000020." These operations will be repeated during the rotation of the drum 25 until the tens wheel has advanced nine steps and the units wheel has thereafter advanced nine steps. Then, the recesses 33 of both of these wheels will be disposed in axial alinement and the corresponding actuating 30 fingers will have dropped into the same, thus bringing the actuating finger for the hundreds wheel into engagement with the ratchet tooth thereof disposed immediately in rear of the recess 33 therein. At the 35 next semi-rotation of the printing drum, all three of these typewheels will be advanced one step, bringing the ciphers on the tens and units wheels into operative position and the numeral "1" on the hundreds wheel into 40 this position. The printing element will now be adapted to print the numeral "000100." When the actuating fingers are subsequently retracted, the one for the unit wheel will become engaged with the ratchet 45 tooth in rear of its recess 33 and will thus elevate all of the remaining actuating fingers into inoperative position. The operations of the actuating fingers will be repeated in the manner just described until all of 50 the typewheels have finally been brought into operation. Then, after the last type-wheel, that for the hundreds of thousands, has moved nine steps from its normal position, and all of the wheels of lower order 55 have been moved until all of the recesses 33 are in axial alinement, then all of the actuating fingers will fall into corresponding recesses and the printing element will be adapted to print the numeral "999999." At 60 the next semi-rotation of the printing drum, all of the typewheels will be advanced one step and the printing element will be ready to print the numeral "000000," which represents one million. At this point, the machine 65 will have printed a complete series of num-

bers from one to one million and will be ready to repeat the series in the same manner as before.

It is to be understood that the typewheels may be grasped readily by inserting the 70 hand through one end of the printing drum when it is desired to adjust them manually in order to reprint any desired number.

The bags to be marked and numbered are fed from a table or feed board 53 positioned 75 at the front of the machine frame. The forward edge of this board overlies a conveyer belt 54, which extends beneath the printing drum and is movably supported upon the front and rear rollers 55 and 56, which are 80 arranged upon the frame of the machine in advance and in rear of the printing drum respectively. The rear roller 56 is fixedly mounted upon a transverse shaft 57 which is journaled in suitable bearings carried by 85 the frame. The front roller 55, however, is journaled between arms 58 which are fixedly secured to a transverse rock-shaft 59 journaled in bearings 60 upon the frame. The arms 58 with the roller carried thereby are 90 yieldably supported in substantially horizontal position by means of the springs 61. Above the roller 55, a co-acting roller 62 is journaled in vertically adjustable bearings 63 which are normally held down by the 95 springs 64. An operating arm 65 projects inwardly from the rock-shaft 59 toward the printing drum and bears, through the medium of an anti-friction roller, against a cam 66, which is mounted fixedly upon the 100 adjacent trunnion 3 of the drum for rotation therewith. The major portion of the cam is disposed inwardly with respect to the remaining, high portion 67, and both portions are concentric to the drum axis. The roller 105 55 will be maintained by gravity in its lowermost position, spaced from the companion upper roller 62, during the time that the operating arm 65 is in contact with the low portion of the cam. The high portion of 110 the cam is arranged in such relation to the drum slot 6 that it will come into contact with the said operating arm to elevate the roller 55 of the bag conveyer into closer proximity to the superimposed roller 62 for 115 engagement with the incoming bag just before it and the drum slot approach the printing, or impression position. The bag will thus be drawn between these rollers and fed onto the conveyer belt. A pressure exerting roller 68 is journaled beneath the upper stretch of the conveyer 54 for contact therewith in adjustable bearings 69, which latter are yieldably supported by the springs 70. These springs cause the roller 68 to 120 press the said stretch of the belt and any bag which may be supported thereon against the periphery of the printing drum and the type faces thereof, so as to secure a good 125 impression. The said roller is thus neces- 130

sarily positioned directly beneath the axis of the drum at the impression position.

The conveyer is driven from the main, drive shaft 11 by transmission mechanism 5 which appear in detail in Fig. 5 of the drawings. A sprocket-wheel 71 is fixedly secured to the shaft 57 of roller 56 and a related sprocket-wheel 72 is secured to the drive shaft 11. A chain 73 passes around 10 these sprocket-wheels and also extends around the idlers 74, 75 and 76, which are carried by the frame of the machine. Idlers 74 and 75 are journaled in an adjustable member 77, which is secured to the frame in 15 adjusted position by means of the clamping bolt 78. By adjusting the member 77, the tension upon the chain 73 may be readily regulated.

The bag conveyer is arranged so that it 20 delivers the printed bags onto an inclined discharge plate 79 leading to the stacking device, which will be described fully hereinafter.

The inking device for the printing drum 25 is comprised essentially of a hopper or fountain 80, the mixing roller 81, and the train of auxiliary, inking rollers 82, 83 and 84. The mixing roller is driven from the drum trunnions by means of the sprockets 85 and 30 86 and chain 87. It rotates continuously, mixing the ink and maintaining it soft. The flow of ink is regulated by the plates 88 and thumb screws 89 of the fountain. The inking roller 84 is in constant contact with the 35 type faces of the printing drum and its shaft has cylindrical cams 90 near the ends thereof, which roll upon the periphery of the drum. These cams have oppositely inclined inner end faces 91 for operative engagement 40 with collars 92 which are fixed on the shaft of roller 83, whereby the latter is reciprocated axially during its rotation, as caused by peripheral contact with the roller 84. This axial movement of the roller 83 causes 45 the ink which it supplies to roller 84 to be distributed evenly upon the latter. The roller 82 transmits ink from the mixing roller 81 to distributing roller 83, but it performs this function intermittently, since its 50 shaft is acted upon by cams 93 carried by the shaft of the distributing roller. These cams cause the roller 82 to contact with the mixing and distributing rollers alternately. The roller 82 is rotated solely through contact 55 with either of the last-mentioned rollers.

The stacking device will now be described. Journaled in bearings provided on a rearward extension 94 of the machine frame are two parallel pairs of short shaft sections 55 and 96. The sections of each pair are in precise alinement with each other and have sprocket-wheels 97 upon their inner ends. Conveyer chains 98 are operatively engaged with the sprockets of corresponding shaft 65 sections of both pairs, and are thus disposed

at the opposite sides of the machine and extend from front to rear in substantially parallel relation to each other.

The outer end of each section of shaft 95 is provided with a sprocket-wheel 99, which 70 is connected by chain 100 with a sprocket-wheel 101 on a shaft 102 journaled in the main frame of the machine. Another sprocket-wheel 103 on shaft 102 is connected by a chain 104 with a sprocket 105 carried 75 by one member 106 of a friction clutch on shaft 57. This clutch member is loosely mounted on the shaft 57 and is pressed against a co-acting clutch member 107 by spring 108. The last-mentioned clutch 80 member is fixed upon the shaft 57, so is adapted normally to transmit motion from said shaft to the clutch member 106, but affords an impositive drive for the conveyer 85 chains of the stacking device.

A number of transversely extending bag carriers 109 (two in the present instance,) are connected at their opposite ends with the conveyer chains 98 for translatory movement therewith. The carriers are preferably 90 situated as far apart longitudinally on the chains as possible, and they are provided adjacent to their opposite ends with pivoted fingers or grippers 110. These grippers are normally maintained in closed, operative position, as shown most clearly in Fig. 3 of the drawings by means of springs 111. An arm 112 projecting from each gripper is adapted to contact with a gripping cam 113 mounted stationarily in the machine frame, where- 95 by the grippers are opened just before the corresponding bag carrier reaches its catching position below the discharge plate 79.

In order that either bag carrier may be retained in catching position, with its grippers 105 open, until a bag has fallen onto the same, a hook member 114 in the form of a lever is pivotally mounted on the machine frame and is maintained by the spring 115 normally in operative position wherein it will engage the 110 bag carrier automatically upon arrival at catching position. A releasing lever 116, which is operatively connected with the hook 114, has an arm situated normally in the path of movement of an actuating projection 115 117 provided on the printing drum 2. This projection is timed so that it will strike the lever 116 and trip the hook 114 at the proper moment. The said hook is permitted to check the movement of the bag carriers in 120 the manner described, owing to the impositive drive action afforded by the clutch members 106 and 107.

When a bag has fallen upon one of the bag carriers, it will have just resumed its normal 125 movement and the grippers will now be released so as to grip the bag, which is carried along to a position directly above the place upon the floor where a pile is to be, or has been, made. At this point, the grippers are 130

opened by contact with the tripping cams 118 carried by the frame extension 94. Upon being released, each bag will fall outstretched upon the pile.

5 Having thus described my invention what I claim and desire to secure by Letters-Patent of the United States of America is:

1. In a machine for marking and numbering bags, the combination of printing means, 10 bag feeding means, and a stacking device including a conveyer, bag carriers provided on the said conveyer and having grippers adapted to grip the printed bags as they are successively received from the bag feeding 15 means, means for normally maintaining the grippers of each bag carrier in closed position, means for opening the grippers of each carrier as the latter arrives at its bag receiving position in operative relation to the 20 bag feeding means and for subsequently releasing the said grippers, means for opening the grippers of each bag carrier as the latter reaches its stacking position, impositive driving means for the said conveyer, means 25 for checking the movement of the conveyer as each bag carrier arrives at its bag receiving position, and means timed by the movement of the bag feeding means for releasing the said checking means at the moment 30 of discharge of a bag from the said feeding means onto the said bag carrier.

2. In a machine for marking and numbering bags, the combination of a stationary frame, a printing drum journaled in the 35 frame and provided on its periphery with type faces and having a longitudinal slot in its peripheral wall, bag feeding means associated with the drum, a numbering element mounted in the drum, and consisting of an 40 axial shaft mounted for radial adjustment in the drum, a plurality of type wheels mounted upon the shaft for independent adjustment and adapted normally to have their type faces project through the drum slots in operative, printing position, means for adjusting the said shaft within the drum and for securing it in adjusted position, an operating device for the type wheels movably associated therewith, an operating crank shaft 45 for the said operating device, a connecting

rod connecting the crank of said shaft with the operating device, the said crank shaft being composed of two sections, one of said sections being free from connection from the said connecting rod and projecting exteriorly 55 from the drum, a clutch device adapted to connect the said shaft sections together for movement, means by which the said clutch may be shifted, actuating means provided upon the exteriorly projecting shaft section, 60 and means carried by the frame for coöperating with the last-named means to rotate the said shaft sections during rotation of the drum.

3. In a machine for marking and numbering bags, the combination of printing means, bag feeding means, and a stacking device including a conveyer, bag carriers provided on the said conveyer and having grippers adapted to grip the printed bags as they are 70 successively received from the bag feeding means, means for normally maintaining the grippers of each bag carrier in closed position, means for opening the grippers of each carrier as the latter arrives at its bag receiving position in operative relation to the bag feeding means and for subsequently releasing the said grippers, means for opening the grippers of each bag carrier as the latter reaches its stacking position, impositive driving means for the said conveyer, a releasable stop member adapted normally to project into the path of the bag carriers for checking engagement with each carrier upon arrival at its bag receiving position, releasing 75 means for the said stop member including a movable actuating member, and a trip device provided on the printing means and adapted to operatively engage the said actuating member at the moment of discharge of a bag 80 from the said feeding means onto the said bag carrier.

In testimony whereof I have signed my name to this specification in the presence of two subscribing witnesses.

ALFREDO BENITO VASQUEZ.
